J. E. ARRANTS.
TOBACCO CUTTER.
APPLICATION FILED OCT. 20, 1913.

1,106,858.

Patented Aug. 11, 1914.

UNITED STATES PATENT OFFICE.

JAMES E. ARRANTS, OF ELIZABETHTON, TENNESSEE.

TOBACCO-CUTTER.

1,106,858.

Specification of Letters Patent. Patented Aug. 11, 1914.

Application filed October 20, 1913. Serial No. 796,329.

To all whom it may concern:

Be it known that I, JAMES E. ARRANTS, a citizen of the United States, residing at Elizabethton, in the county of Carter and 5 State of Tennessee, have invented a new and useful Tobacco-Cutter, of which the following is a specification.

The present invention appertains to tobacco cutters.

- 10 The present invention contemplates the provision of a tobacco cutter embodying a reciprocating cutter disk, in combination with novel means for guiding and actuating the same, the present device being comparatively simple, substantial, durable and inexpensive in construction, and being capable of compact shipment or storage without detaching or separating the component parts of the cutter.
- 15 Among its other objects the present invention aims to provide anti-frictional means for the cutter disk, means whereby the cutter disk may be automatically cleaned, and means for shielding or guarding the upper portion of the cutter disk.

With the foregoing general objects outlined, and with other objects in view, which will be apparent as the nature of the invention is better understood, the present invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention has been illustrated in its preferred embodiment in the accompanying drawing, wherein:—

Figure 1 is a plan view of the improved tobacco cutter, illustrating the handle or lever swung to closed or folded position, a portion of the handle or lever being broken away. Fig. 2 is a side elevation of the improved cutter, illustrating the lever swung open in full lines, and swung to closed or folded position in dotted lines. Figs. 3 and 4 are enlarged cross sectional views taken on the lines 3—3 and 4—4 of Fig. 2, respectively, with the handle or lever illustrated as being swung to folded or closed position.

In carrying out the present invention, there is provided a base comprising the two longitudinal sections or plates 1, the adjoining or inner edges of which are spaced

slightly apart intermediate the ends of the base, to provide a slot 1^a. The sections 1 of the base are also provided with any suitable means for fastening the base upon a counter, 60 table, or any other suitable object.

Each of the base sections 1 is provided with an integral arch at its inner edge, the arch constituting upright portions or standards 2 connected at their upper ends by the 65 bar or yoke 3. The ends or upright portions 2 of the arches are spaced sufficiently from the ends of the base, the two arches complementing each other to form a guide for the cutter disk hereinafter referred to. The intermediate portion or yoke 3 of one of the arches is raised, as at 4, to form a shield or guard for the cutter disk.

Beyond the ends of the arches, the base sections 1 are provided adjoining their inner edges with the ears 5, the ears at each end, complementing each other, and having a draft or clamping bolt 6 passed therethrough, to adjustably connect the sections of the base, for the purposes which will 70 75 80 hereinafter appear. The base sections are also provided with transverse or lateral ribs or flanges 7, flush with the inner edges of the ends or upright portions 2 of the arches, and against which the plugs of tobacco are 85 adapted to rest or seat. One or more of the ribs or flanges 7 may be graduated, as at 7^a, in order that the plugs of tobacco may be accurately cut to length.

The foregoing parts constitute two members, which may be readily cast from any suitable metal, it being apparent that the respective arches, ears 5, and ribs 7 are integral with the base sections.

The cutter disk 8 is disposed between the 95 arches so as to work within the slot 1^a of the base, the cutter disk being designed to reciprocate longitudinally between the yokes or intermediate portions 3 of the arches, and being designed to pass between the ends or 100 upright portions 2 of the arches. The cutter disk 8 has an axle 9 engaged therethrough, which is movable along the under run of the bars or yokes 3 of the arches, to properly guide the cutter disk. To the ends 105 of the cutter disk axle 9 are connected links 10, which are disposed at the opposite sides of the arches, and which are connected to the lever or handle, as hereinafter described.

Washers 11 are mounted upon the axle 9 110 between the cutter disk and the links 10 and are designed to engage the under runs

of the guide bars or yokes 3 of the arches, to provide anti-frictional roller bearings for the cutter, in order that the cutter may move freely along the arches. A lever or handle 12 is pivoted to one end of the base, as will hereinafter appear, and is provided with an offset 13 adjoining its fulcrum or pivotal point, and with a second offset 14 adjoining its free end, and providing a hand hold 15. The primary offset 13 is arranged to swing over one corner of the arch 3, which does not have the guard 4, while the portion 16 of the lever intermediate the primary and secondary offsets 13 and 14, respectively, is designed to swing over the said arch, adjoining the guard 4. The lever 12 is provided with an outstanding ear 17 adjoining the primary offset 13, through which a bolt or pivot member 18 is passed, the links 10 being engaged to the respective ends of the bolt or pivot member 18.

The lever 12 is fulcrumed or pivoted to the base in the following manner. The base sections 1 are provided at one end with upward standing ears 19 at the inner edges, which receive the end of the lever 12, a bolt or fulcrum member 20 being passed through the ears 19 and the end of the lever. The ears 19 are also integral with the base sections to be molded therewith.

From the foregoing, taken in connection with the drawing, it will be evident that the several parts of the device may be inexpensively manufactured, and may be readily assembled.

In operation, the plugs of tobacco to be cut or severed, are placed against the respective ribs 7, and by swinging or oscillating the lever 12, the cutter disk may be moved or reciprocated endwise to sever the plugs of tobacco, it being observed that the plugs of tobacco may be severed at both ends of the arches or guide. The guard or shield 4 protects the upper portion of the cutter disk in order that the hands may not come in contact with the upper portion of the cutter, and in order that the upper edge of the cutter may not be injured. By loosening or tightening the draft bolts 6, the base sections may be adjusted relative to each other, to correspondingly space the arches or guide members, and to correspondingly close or open the slot 1. This is of advantage for the reason that the arches or guide members and the inner edges of the base sections may be moved to and from each other, in order to accomplish a proper or efficient movement of the cutter disk therebetween, it being evident that when the arches or guide members are clamped together over the cutter disk, the cutter disk will be automatically cleaned.

The present device may be folded together compactly, as illustrated in Fig. 2, by the dotted line position of the lever. Thus,

when the lever is swung downwardly, the intermediate portion 16 thereof is adapted to swing adjoining the guard 4 upon the opposite arch, and the hand hold 15 alone will be left projecting, the hand hold being disposed over the cutter disk, and not appreciably encumbering the device when folded. In this condition, the device may be compactly boxed or shipped for sale.

From the foregoing, taken in connection with the drawing, the other advantages of the present device will be apparent without further comment; it being observed that the objects aimed at have been carried out satisfactorily.

Having thus described the invention, what I claim as new is:

1. In a device of the character described, a base comprising two sections, the base sections having complementing arches at their adjoining edges, means adjustably connecting the sections of the base, the intermediate portions of the arches constituting guide bars, a cutter disk movable between said guide bars, an axle carried by the cutter disk and working along the lower run of the guide bars, a lever fulcrumed to one end of the base, and links connecting the lever and the ends of said axle.

2. In a device of the character described, a base embodying two longitudinal sections having their adjoining edges spaced apart intermediate their ends to provide a slot, the base sections having complementing arches at their adjoining edges, and ears beyond the ends of the arches at the adjoining edges, draft bolts connecting the said ears, the intermediate portions of the arches forming guide bars, a cutter disk movable between the said guide bars and in the said slot, an axle for the cutter disk movable along the under run of the guide bars, a lever fulcrumed to one end of the base, and links connecting the lever and the ends of the said axle.

3. In a device of the character described, a base having a pair of arches, the intermediate portions of the arches constituting guide bars, a cutter disk movable between the said guide bars, one of the guide bars being raised to form a guard for the cutter disk, an axle for the cutter disk movable along the under run of the guide bars, a lever fulcrumed to the base beyond the arches and arranged to swing over the other guide bar, and links connecting the lever and the ends of the axle.

4. In a device of the character described, a base having a pair of arches, the intermediate portions of the arches forming guide bars, a cutter disk movable between the guide bars, an axle for the cutter disk movable along the under run of the guide bars, a lever fulcrumed to one end of the base beyond the arches, the lever having a primary

offset to engage over the adjoining corner of one arch, and having a secondary offset adjoining its free end to provide a hand hold, the portion of the lever intermediate the offsets being seatable upon the said arch, and links connected to the ends of the said axle and to the said lever adjoining the primary offset.

5. In a device of the character described, 10 a base embodying two longitudinal sections having their adjoining edges spaced apart intermediate their ends to provide a slot, said sections having complementing arches at their adjoining edges, a pair of complementing ears at their adjoining edges beyond the respective ends of the arches, and a pair of complementing ears at one end, the intermediate portions of the arches constituting guide bars, one guide bar being raised 15 to form a guard, draft bolts connecting the first mentioned ears, a fulcrum bolt engaged through the second mentioned ears, a cutter 20

disk movable between the said guide bars and in the said slot, an axle for the cutter disk movable along the under run of the 25 said guide bars, a lever having one end fulcrumed to the said fulcrum bolt between the second mentioned ears, the lever having a primary offset adjoining its fulcrum point to engage over the respective corner of one 30 arch, and having a secondary offset adjoining its free end forming a hand hold, the portion of the lever intermediate the offsets being seatable upon the said arch adjoining the aforesaid guard, and links connecting the ends of the said axle and the lever adjoining the primary offset.

In testimony that I claim the foregoing as my own, I have hereto affixed my signature in the presence of two witnesses.

JAMES E. ARRANTS.
